Attorney

UNITED STATES PATENT OFFICE.

GEORGE BRANDER, OF SUTHERLAND, IOWA.

EGG-TESTER.

1,322,755.

Specification of Letters Patent. Patented Nov. 25, 1919.

Application filed February 17, 1919. Serial No. 277,412.

To all whom it may concern:

Be it known that I, GEORGE BRANDER, a citizen of the United States, residing at Sutherland, in the county of O'Brien and State of Iowa, have invented certain new and useful Improvements in Egg-Testers, of which the following is a specification, reference being had to the accompanying drawings.

10 This invention relates to certain improvements in egg testers, and has relation more particularly to a device of this general character wherein light is projected through the eggs being tested, and it is an object of the 15 invention to provide a novel and improved device of this general character whereby the working operations may be materially facilitated.

It is also an object of the invention to 20 provide a device of this general character whereby a tray is employed provided with egg openings and beneath which openings is arranged a light-containing chamber together with a supplemental tray to receive 25 the bad eggs.

An additional object of the invention is to provide a novel and improved tester of this general character wherein the eggs being tested have their longitudinal axes substantially horizontally disposed so that a 30 more effective test may be obtained.

The invention consists in the details of construction and in the combination and arrangement of the several parts of my 35 invention whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:

Figure 1 is a longitudinal vertical sectional view of an egg tester embodying my invention; and

Fig. 2 is a top plan view thereof.

50 As disclosed in the accompanying drawings, T denotes a bottom tray or pan adapted to be positioned upon a suitable support, and which is defined by the outstanding marginal flanges 1.

55 As herein embodied, the tray or pan T is rectangular in form and secured to the

corner portions thereof are the upstanding posts 2 secured at their upper end portions to a second tray or pan T'.

The pan T' is also defined by upstanding 60 marginal flanges 3. The tray or pan T' adjacent an end at substantially its transverse center is provided with a pair of slots 4 which are adapted to receive the eggs to be tested, and the major axis of each of said 65 slots is such to permit the longitudinal axes of three eggs to be substantially horizontally disposed within said slot so that the testing thereof may be materially facilitated. The longitudinal margins defining each of 70 the openings 4 are substantially in parallelism, so that during a candling operation the eggs arranged within said opening may be readily rotated about their longitudinal axes, in order to effect a thorough testing of the 75 eggs.

H denotes a housing preferably formed of metal and which is secured to the under surface of the tray or pan T' and which housing is arranged below the slots 4. The 80 outer end 5 of the housing H is removable, and for which reason said removable end 5 has its side marginal portions and lower margins defined by the outstanding flanges 6 provided with openings 7 adapted to register with openings 8 in the outer end of the walls of the housing H and through which 85 registering openings the holding bolts 10 are directed.

Secured to the inner face of the removable 90 end 5 is a block 11 to which is secured a conventional type of socket 12 for the electric lamp L. The socket 12 has suitably connected thereto the conductors 14 also suitably connected with the plug 15 and which 95 plug is adapted to be engaged with a suitable source of electrical energy. The lamp L is of the well known incandescent type and when applied within the housing H is substantially horizontally disposed and arranged below the slots 4 so that the rays emitted from said lamp will be directed 100 through the eggs applied within the slots 4.

As before stated, the housing H is of 105 metal, preferably tin, so that the walls of said housing will serve as a reflecting medium to throw an exceedingly strong light on the eggs within the slots 4.

The lower tray or pan T furnishes a 110 convenient place to put the bad eggs while testing so that very fast work can be obtained because two canders may be em-

ployed with each device at the same time, one of said canders applying the eggs to and from the slots 4, while the second party removes the good eggs from the upper tray 5 or pan T' and applies the same within a case or other container.

From the foregoing description, it is thought to be obvious that an egg tester constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of

the several parts herein shown in carrying out my invention in practice except as here- 20 inafter claimed.

I claim:—

An egg tester including a tray provided with a slot of a length to receive a plurality of eggs, whereby the eggs may be arranged 25 within the slot with their axes substantially longitudinally alined and rotated about their axes, and means for directing light through the opening.

In testimony whereof I hereunto affix my 30 signature in the presence of two witnesses.

GEORGE BRANDER.
